LOCK

Albert J. Pacewick, Chicago, Ill.

Application September 12, 1935, Serial No. 40,201

4 Claims. (Cl. 70—308)

This invention relates to that general class of devices known as locks, and more particularly to a novel and improved construction of locking mechanism which may be operated substantially 5 as a permutation lock.

An object of this invention is to provide a locking mechanism of the character described adapted for association with the fuel supply line of an automobile, whereby the supply line may 10 be locked against tampering by unauthorized persons.

Another object of the invention is to provide a novel and improved locking mechanism for the fuel supply line of an automobile disposed within 15 the fuel supply for locking the same, said locking mechanism being substantially pick-proof and being arranged for easy manipulation by the operator of the vehicle from the dash board thereof.

A further object of this invention is to provide 20 a locking mechanism of the character described for the fuel supply of an automobile which may be readily and conveniently attached in the fuel supply without necessitating the modification or altering of the same, and when in fully assembled 25 position with the fuel supply line, the same may be readily manipulated by authorized persons from the dash board of the vehicle.

A still further object of this invention is to provide 30 a novel and improved locking mechanism of the character described which will consist of a minimum of parts, which may be readily assembled and which, therefore, may be produced at a cost convenient for mass production, but which at the same time will be highly efficient for carrying 35 out the purposes for which it is designed.

With the foregoing and other objects in view which will appear as the description proceeds, the invention consists in certain novel features of construction, arrangement and combination of 40 parts hereinafter fully described, illustrated in the accompanying drawings, and particularly pointed out in the appended claims, it being understood that various changes in the form, proportion, size and minor details of the structure 45 may be made without departing from the spirit or sacrificing any of the advantages of the invention.

For the purpose of facilitating an understanding of my invention, I have illustrated in the accompanying drawings, a preferred embodiment 50 thereof, from an inspection of which when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawings:

Figure 1 is a view illustrating my improved 5 locking mechanism associated with the engine of a motor vehicle;

Fig. 2 is a front elevational view of my improved locking actuating mechanism mounted 10 on the dash board of the vehicle;

Fig. 3 is a sectional view taken substantially 15 on line 3—3 of Fig. 2;

Fig. 4 is a view taken substantially on line 4—4 of Fig. 3, looking in the direction of the arrows;

Fig. 5 is a view taken substantially on line 20 5—5 of Fig. 3;

Fig. 6 is a rear elevational view of the actuating 25 mechanism mounted on the dash board of the vehicle;

Fig. 7 is a sectional view taken substantially 30 on line 7—7 of Fig. 6;

Fig. 8 is an elevational view of my improved operating mechanism with which the combination 35 to the lock may be set up;

Fig. 9 is a sectional view through said operating mechanism taken substantially on line 9—9 of Fig. 8;

Fig. 10 is a top plan view of the universal joint connecting the actuating mechanism on the dash 30 board with the valve means associated with the engine;

Fig. 11 is a top plan view, partly broken away, through the locking mechanism associated with the engine;

Fig. 12 is a sectional view through the locking mechanism taken substantially on line 12—12 of Fig. 11;

Fig. 13 is a view looking into the valve casing with the locking mechanism for setting up the 40 combination removed;

Fig. 14 is a sectional view taken substantially on line 14—14 of Fig. 12;

Fig. 15 is a sectional view through one of the valve operating members taken substantially on 45 line 15—15 of Fig. 12;

Fig. 16 is a view taken substantially on line 16—16 of Fig. 12;

Fig. 17 is a view taken substantially on line 17—17 of Fig. 12;

Fig. 18 is a view taken substantially on line 18—18 of Fig. 12; and

Fig. 19 is a view similar to Fig. 16 with the actuating disk disposed in a different position of operation.

Referring to the drawings more specifically by characters of reference, the letter A designates generally my improved locking mechanism attached to the carburetor C of an automobile engine E, said mechanism having associated with it the shaft 10 which extends therefrom, and the free end of which is connected by means of a suitable universal joint 11 to a shaft 12, the latter shaft being associated with the actuating mechanism, generally designated by the letter B, and which is mounted on the dash board D of the vehicle.

The carburetor is provided with a threaded nipple 13 which in the present case may be made of highly tempered steel to prevent the same from being readily cut away or severed from the carburetor. To the nipple 13 is adapted to be secured in threaded relation the box-like member 14 substantially one-half of which is hollowed out to form the compartment 15 for receiving and housing the locking mechanism to be hereinafter more fully described.

Within the other portion of the member 14 is provided a fuel passage 16, one end of which communicates with the nipple 13, and in the other end of which is threaded a second nipple 17 leading from the fuel supply line (not shown) whereby communication may be established between the fuel supply line and the carburetor C through the medium of the passage 16. Provided in the member 14 intermediate the ends of the passage 16 is a tapered valve seat 18 within which is adapted to be received a tapered valve member 19, which valve member is integrally formed with the disk member 20. The free end of the valve member 19 is of reduced diameter and is externally threaded to form an extension 21, which extension extends through a somewhat enlarged bore 22 to the outside of the member 14, as shown in Fig. 12. When in fully assembled position, the threaded extension 21 is surrounded by a coil spring 23, said spring having one end bearing against the shoulder 24 and the other end against a washer 25, said washer and spring being adjustably held in place by a pair of lock nuts 26 threaded on the free end of the extension 21.

The valve member 19 has a transverse passage 27 extending therethrough, which passage may be arranged for alignment with the passage 16 when it is desired to establish communication to the carburetor, and which may be moved through an angle of 90° in a manner to be hereinafter more fully described when it is desired to prevent such communication. The provision of the spring 23 will be effective for causing a tight fit of the valve 19 in its seat 18 at all times, said spring compensating for any wear of the valve member.

In order to prevent the unauthorized removal of the member 14 with its associated mechanism, I have provided adjacent one corner of the member 14 a bore 28 which extends completely through the member 14, as shown in Fig. 11, within which bore is adapted to be received a rod 29 which may be made of highly tempered steel, one end of said rod extending beyond the member 14 and in position to be engaged by the carburetor C when it is desired to rotate the member 14 in order to detach the same from the nipple 13. The rod 29 is permanently secured in place in the bore 28 by the pin 30 which extends through a transverse passage provided in the rod, which passage is in alignment with the opening provided in the wall of the member 14 for the passage of said pin 30. By reason of the fact that the rod 29 is of highly tempered steel, it will be readily apparent

that it will be practically impossible to readily sever the same should an unauthorized person attempt to remove the locking mechanism from the carburetor.

As already stated, the valve 19 is formed integrally with the disk 20, which disk has a portion thereof cut away, as shown at 31, Fig. 15, and within which cut away portion is pivotally mounted, as shown at 32, a member 33, the free end of which is connected to one end of a coil spring 34, the other end of which spring is connected to a fixed pin 35, said spring normally urging said member 33 in a clockwise direction as viewed in Fig. 15. Extending from said member 33 is a pin or stud 36, which pin is disposed in a notch 37 provided on one face of the disk 20, said notch co-operating with the pin 36 for limiting movement of the pivoted member 33 in either direction.

The disk 20 is adapted for disposition on the bottom wall of the compartment 15 with the pin 36 extending therefrom towards the open end of said compartment. The disk 20 is also provided with a central recess 38 within which is adapted to be received the rounded edge 39 of the free end of the shaft 10, said end being disposed for free rotation in said recess, the latter forming a bearing for said end of the shaft.

Rigidly secured to said shaft immediately adjacent its free rounded end 39 is a disk 40, said disk being somewhat smaller in diameter than the disk 20 and being provided with a peripheral notch 41 within which is adapted to be received the pin 36 when the device is in assembled position. One side wall of said notch is cammed, as shown at 42, so as to permit rotation of the disk 40 relative to said disk 20 in one direction, but the two will turn together when moved in the other direction. It will also be noted that when in assembled position, the spring 34 will normally urge the pin 36 into engagement within the notch 41, the diameter of the disk 40 being such that when the pin 36 rides on the outer periphery thereof, the pivoted member 33 will be moved against the tension of spring 34 to the limit of its anti-clockwise movement, as viewed in Fig. 15. Extending towards the open end of the compartment 15 is a stud or pin 43 rigidly secured to one face of the disk 40 for a purpose to be presently more fully described.

In order to set up the combination for coupling the disk 20 to the disk 40 whereby rotary movement may be imparted to the disk 20 and valve member 19 associated therewith through the shaft 10 when it is desired to actuate said valve, I provide a plurality of fixed disks 44, 45 and 46, all of which disks are connected in spaced relation to each other by means of the spacer members 47 and 48 disposed adjacent opposed sides of said disks 44, 45 and 46. Any suitable means may be employed for connecting said disks to each other, and in the embodiment illustrated, I employ the headed screws 49, which screws extend through the disks 44, 45 and 46 as well as the spacer members 47 and 48 disposed between said disks. In addition to being secured to each other, said disks are also connected by means of the same screws 49 to a cover plate 50 which is adapted for completely enclosing the compartment 15. Suitable nuts 51 may be provided on the free ends of said screws 49 for completing the assembly of the disks to each other.

Each of the disks 44, 45 and 46 is provided with a central opening 52, a portion of the periphery of which opening is cut away, as shown

5

15

25

35

40

45

55

60

65

70

75

in Fig. 17, to form the shoulder 53 and notch 54, the portion 55 between the notch 54 and shoulder 53 being of somewhat enlarged diameter. Disposed between each of the fixed disks 44, 45 and 46 and cover plate 50 are the annular disks 56, 57 and 58, each of which is loosely mounted on the shaft 10 for rotation thereon. The diameter of said annular disks is such that it is larger than the diameter of the opening 52, but slightly smaller than the diameter of the portion 55 of said opening.

Provided in each of said disks 56, 57 and 58 is an arcuate slot 59 within which is adapted to be received the pin or stud 43 extending from the disk 40 when the mechanism is in fully assembled position. The arcuate slots 59 are arranged so that they may be disposed in alignment with each other, but each slot is of a different size in length from the slots in the other two disks. The pin 43 is of such a length as to extend into the slots 59 of all of the disks 56, 57 and 58. In addition to the arcuate slots 59 provided in the annular disks, these disks are also provided with a peripheral notch 60, which notches are adapted for alignment with each other and with the notch 41 in the disk 40 and when so aligned will receive the pin or stud 36 extending from the pivoted member 33.

In order to prevent accidental movement of the disks 56, 57 and 58, I have provided spring clip members 61 having the arms 62 which engage the periphery of the annular disk and thereby frictionally hold the same in any position to which it may have been moved. Said spring clip members 61 are held in assembled position by means of the screws 63 which extend through the plate members 44, 45 and 46 and cover member 50. Nuts 64 are threaded on the free end of said screw member 63 to complete the assembly of the mechanism.

From the construction above described, it will be apparent that when the mechanism is in the position shown in Fig. 19, the stud 36 will be received within the notches 54 of the fixed plate members 44, 45 and 46, in which position the pivoted member 33 will be held against the tension of the spring 34 by the peripheries of the disks 56, 57, 58 and 40 at the limit of its counter-clockwise movement. In this position, it will be noted that the valve 19 will be in its closed position, thereby preventing communication between the fuel supply line and the carburetor.

Now, when it is desired to open said valve, it will be necessary to manipulate the disks 56, 57 and 58 so as to move the notches 60 thereof into alignment with each other as well as in alignment with the notches 54 in the plate members 44, 45 and 46. When the three annular disks have been so aligned, the bringing of the notch 41 into alignment with the notches 54 will cause the spring 34 to move the stud 36 out of the notches 54 and into the notch 41 and notches 60. Further movement of the disk 40 in a clockwise direction will be effective for actuating the disk 20 by reason of the engagement of the pin 36 within the notch 41, which movement will take place until the pin 36 is brought into engagement with the shoulder 53 at which time the valve will be completely opened. The mechanism may be permitted to remain in this position with the valve 19 in open position until the operator is ready to leave the vehicle and again lock the supply line.

In order to move the valve 19 to its closed position, it is only necessary to rotate the shaft 10

and its associated disk 40 in a counter-clockwise direction until the stud 36 is brought to a position opposite the notches 54. Further rotation of the shaft and disk 40 will cause the stud 36 to ride on the cammed surface 42 of the notch 41 in the disk 40 with the result that the stud 36 will be forced to enter the notches 54, in which position the valve 19 will be closed. The stud 36 will now ride or rest against the periphery of the disk 40 and it will not be possible to again open the valve until the proper combination has been set up for bringing all of the notches 60 as well as the notch 41 in complete alignment with each other at the point directly opposite the notches 54, at which time the stud 36 will again snap into the notches 60 and 41 so that further rotation of the shaft 10 in a clockwise direction until the stud 36 is brought into contacting engagement with the shoulder 53 will bring the valve 19 again into fully opened position.

In order to set up the combination from the dash board, the shaft 10 has provided on its free upper end a sleeve 70 rigidly secured thereto, the upper end of said sleeve being bifurcated to form the arms 71, said arms receiving therebetween the cylindrical rod 72, to which the sleeve 70 is pivotally secured by means of the pin 73 extending through said arms and through said rod. Pivotally mounted on the rod 72 for rotation thereon in a plane substantially perpendicular to the plane of rotation of the sleeve 70 is a sleeve 74 having the ears 75 in which is disposed the free ends of the rod 72. Pins 76 are passed through the rod 72 adjacent its free ends for preventing disassociation of the sleeve 74 from the rod 72.

The sleeve 74 has rigidly secured thereto one end of a shaft 77, the other end of which is flattened on both sides to produce the portion 78, which portion is received between the bifurcations 79 of a shaft 80 journaled for rotation in the casing B secured to the dash board of the vehicle in any suitable and well known manner, such, for example, as by means of the screws 81. To prevent disengagement between the shafts 77 and 80, a sleeve 82 is provided for surrounding the said shafts at their point of juncture. To facilitate the rotation of the shaft 80, the same has provided on its free end a suitable handle or knob 83 which is rigidly secured thereto.

The following novel means are provided for actuating the shaft 10 to set up the combination for opening the valve 10 when it is desired to open the fuel supply line to the carburetor. The casing B is provided with an annular flange 84, which flange is adapted to rest against the dash board D and to form with said dash board the closed compartment 85.

The flange 84 is provided with a slot 86 which is of a size and shape to permit the passage therethrough of the operating member 87 for insertion into the compartment 85. The casing B is so disposed on the dash board as to have the slot 86 therein arranged at its upper end, as shown in Figs. 3 and 4, whereby the operating member 87 may be readily held in operative position therein. A suitable guide 88 is provided on the inner face of the casing B, said guide being in communication with the slot 86 and is adapted to receive therein the shank portion of the operating member 87, as shown in Fig. 4.

Rigidly secured to the shank portion of the operating member 87 is a plate member 89, which plate member is provided with a plurality of cut-out portions 90, 91 and 92, said cut-out portions 95

being arranged in any desired staggered relation, thereby varying the particular combination of the lock. The guide member 88 is of a thickness substantially equal to the thickness of the operating member 87, so that when the said operating member is in operative position within the casing B, as shown in Figs. 3 and 4, the plate member 89 will project beyond the guide member 88, as shown more clearly in Fig. 3.

10 Co-operating with said operating member is an annular disk 93 which is adapted for disposition within the compartment 85 for rotation therein, said disk having an inwardly extending annular flange 94 and a rearwardly extending bushing 15 95 through which the shaft 80 is adapted to pass. A pin 96 passing through said shaft and bushing is provided for locking said shaft to said disk, whereby the latter will rotate with the shaft. The annular flange 94 provided on the disk 93 is 20 cut away along two points of its perimeter approximately 90° apart as shown at 97 and 98 in Fig. 5, for permitting the passage of the operating member 87 as the annular flange 94 normally engages the inner wall of the casing B and 25 thereby closes the passage 86 in the flange 84 of said casing.

The disk 93 is provided with a plurality of studs extending therefrom, the number of said studs corresponding to the number of cut-away portions 30 provided in the plate member 89. Thus in the embodiment illustrated, said member 93 is provided with the fixed studs 99 and 100 and the yieldable stud 101.

Said studs extend inwardly towards the inner 35 wall of the casing B and are arranged when the operating member is in operative position to engage within the cut-out portions 90, 91 or 92 to co-operate therewith for setting up the combination of the locking mechanism. Thus, in the embodiment illustrated, the stud 100 will co-operate with the notch 92, the stud 99 will co-operate with the notch 90 and the movable stud 101 will co-operate with the notch 91, said studs engaging their co-operating notches as the disk 93 is rotated, thereby setting up the combination of the locking mechanism.

The plate member 89, as shown in Fig. 9, is provided with a curved edge 102 to permit the passage thereover of the movable stud 101 when 50 the disk 93 is moved in a clockwise direction, as viewed in Fig. 4. The movable stud 101 is secured to one end of a flexible member 103, the other end of which is rigidly secured to the disk 93 in any suitable and well known manner, such, 55 for example, as by the rivets 104. The stud 101 extends through an opening 105 provided in the disk 93.

In order to manipulate the mechanism for setting up the combination, it is necessary to first 60 move the disk 93 to a position where the cut-out portion 97 in the annular flange 94 thereof will be disposed in alignment with the slot 86 in the casing B. In order to determine when such position has been reached, I have provided a spring 65 member 106, one end of which is rigidly secured to the knob 83, as shown at 107 in Fig. 3. The other free end of said spring member 106 is adapted to engage within a recess 108 when the knob is disposed in position where the cut-out 70 portion 97 is in alignment with the slot 86. It will thus be possible to align said openings for the reception of the operating member 87 by the clicking sound caused by the free end of the spring 106 entering the recess 108. When so aligned, 75 the operating member 87 is inserted into the com-

partment 86 and the combination is now ready to be set up.

The knob is then rotated first in one direction to bring the stud 99 into engagement with the notch 90. The knob is then turned in the opposite direction until the stud 100 is brought into engagement with the notch 92. It will be noted that during this rotary movement, the movable stud 101 will be permitted to pass over the operating member 87 which it will be necessary for 10 it to do before the stud 100 is brought into engagement with the notch 92. Rotation in the opposite direction will now bring the stud 101 into engagement with the notch 91. This will complete the setting up of the combination, in 15 which position the notches 60 of the annular disks will be in alignment with the notch 41 in the disk 40 as well as in position opposite the notches 54 for receiving the stud 36. Further rotation in a clockwise direction will actuate the valve disk 20 20 to bring about the opening of said valve, which opening will be completed when the stud 36 engages the shoulder 53.

At this time it will also be noted that the cut-out portion 98 provided in the annular plate 94 25 will be in alignment with the slot 86, thereby permitting the removal of the operating member 87. The valve is now completely opened and fuel will be permitted to pass from the fuel supply line to the carburetor. The rotation of the knob in the 30 opposite direction through an angle slightly greater than 90° will bring about a closing of said valve and the fuel supply line will again be locked.

The operation of the device should be readily apparent and it will also be apparent that I have 35 provided a novel and improved locking mechanism which will be substantially theft-proof and will, therefore, protect the vehicle with which it is associated from unauthorized use. It will also be noted that I have not only provided novel 40 and improved means for closing and opening the fuel valve leading to the carburetor, but have also provided highly convenient means for manipulating the mechanism for setting up the combination. The device has also associated 45 with it improved means for preventing the ready removal thereof from the vehicle, and if desired, in practice, the casing 14 may be formed integral with the carburetor C so that the same may not be disconnected from the carburetor thereby 50 adding an additional feature of safety to the device.

Although in the embodiment illustrated I have 55 shown my improved locking mechanism applied to a fuel line of a motor vehicle, it is to be understood that I do not limit myself to the specific application shown, as the same may be readily adapted and used with equally satisfactory results wherever a locking mechanism is found necessary or desirable.

It is believed that my invention, its mode of 60 construction and assembly, and many of its advantages should be readily understood from the foregoing without further description, and it should also be manifest that while a preferred 65 embodiment of the invention has been shown and described for illustrative purposes, the structural details are nevertheless capable of wide variation within the purview of my invention as defined in the appended claims.

What I claim and desire to secure by Letters Patent of the United States is:

1. A device of the character described, comprising a rotatable member, a shaft, means for coupling said shaft to said member for impart- 75

ing rotary movement through the medium of said shaft to the member, said means including a plurality of spaced super-imposed discs arranged for relative movement to each other, 5 means carried by said shaft for imparting movement to said discs, each of said discs being provided with a peripheral notch, and means carried by said rotatable member for engagement within said notches when the notches in all of 10 said discs are brought into alignment with each other whereby the further rotation of said shaft will impart, through the medium of said discs, rotation to said rotatable member, means associated with said shaft to permit the manipulation 15 of the same to cause said discs to be moved to positions where their peripheral notches will be brought into alignment with each other.

2. A device of the character described, comprising a rotatable member, a shaft, means for 20 coupling said shaft to said member for imparting rotary movement through the medium of said shaft to the member, said means including a plurality of spaced super-imposed discs arranged for relative movement to each other, 25 means carried by said shaft for imparting movement to said discs, each of said discs being provided with a peripheral notch, and means carried by said rotatable member for engagement within said notches when the notches in all of 30 said discs are brought into alignment with each other, whereby the further rotation of said shaft will impart, through the medium of said discs, rotation to said rotatable member, means associated with said shaft to permit the manipulation 35 of the same to cause said discs to be moved to positions where their peripheral notches will be brought into alignment with each other, and means for limiting movement for said rotatable member through an angle of 90° only.

40 3. A device of the character described, comprising a disc having a member pivotally mounted thereon and having a stud extending therefrom, said disc being provided with a peripheral notch for receiving said stud, and means carried by said disc for normally urging said stud in one direction, a rotatable shaft having the free end thereof arranged for rotation within said disc, a second disc mounted on said shaft adjacent the free end thereof for rotation there- 45 with, the diameter of said second disc being 50

such as to engage the stud to hold the same in a projected position, said last-mentioned disc being provided with a peripheral notch within which said stud may be received for coupling said first mentioned disc to said second men- 5 tioned disc, a plurality of annular spaced discs arranged around said shaft, each having a peripheral notch provided therein, means carried by said second mentioned disc for actuating said last mentioned annular discs to bring the same 10 into peripheral relation with each other, in which relation all of said notches will be in alignment with each other and with the notch provided in the second mentioned disc, said stud being adapted for disposition within said notches upon 15 alignment of the same in said predetermined relation, whereby movement of said shaft will impart a corresponding movement to said first mentioned disc.

4. A device of the character described, comprising a disc having a member pivotally mounted thereon and having a stud extending therefrom, said disc being provided with a peripheral notch for receiving said stud, and means carried by said disc for normally urging said stud 20 in one direction, a rotatable shaft having the free end thereof arranged for rotation within said disc, a second disc mounted on said shaft 25 adjacent the free end thereof for rotation therewith, the diameter of said second disc being such 30 as to engage the stud to hold the same in a projected position, said last-mentioned disc being provided with a peripheral notch within which said stud may be received for coupling said first mentioned disc to said second men- 35 tioned disc, a plurality of annular spaced discs arranged around said shaft, each having a peripheral notch provided therein, means carried by said second mentioned disc for actuating said last mentioned annular discs to bring the same 40 into peripheral relation with each other, in which relation all of said notches will be in alignment with each other and with the notch provided in the second mentioned disc, said stud being adapted for disposition within said notches upon 45 alignment of the same in said predetermined relation, whereby movement of said shaft will impart a corresponding movement to said first mentioned disc.

ALBERT J. PACEWICK. 50
